GOVERNOR

Herman G. Adler, Detroit, Mich., assignor to
 Handy Governor Corporation, Detroit, Mich.,
 a corporation of Michigan

Application March 14, 1936, Serial No. 68,952

5 Claims. (Cl. 137—153)

The present invention relates to governors or speed controlling devices for internal combustion engines of the type adapted to be disposed in the intake manifold.

5 More specifically, the invention relates to governors of this class employing an unbalanced valve and means to substantially balance the valve in all positions thereof at a predetermined speed of the motor.

10 Heretofore, where a single spring has been used to balance the valve, it has been necessary to interpose cams, links or other compensating mechanisms between the valve and the spring.

15 The present invention aims to provide a governor that eliminates the cams, links, etc.

To this end, the governor is proportioned so that the closing effect of the flow of gases on the valve transferred to an element subject to reduced pressure in the intake manifold plus 20 the effect of such reduced pressure on the element when plotted against different positions of the element is a straight line. As the same plot for a single spring opposing the element is a straight line, the valve may be balanced in all 25 positions thereof at a predetermined speed of the motor by a single spring.

Other objects and features of novelty will be apparent from the description taken in connection with the drawing, in which:

30 Figure 1 is a sectional elevation taken on line 1—1 of Figure 3 looking in the direction of the arrow;

Figure 2 is a sectional elevation through the device;

35 Figure 3 is a plan view of the governor; Figure 4 is a sectional elevation at right angles to Figure 2;

Figure 5 is a plot illustrating the vacuum force on the piston as plotted against the piston movement;

40 Figure 6 is a plot illustrating the force on the piston due to the torque on the valve plotted against the piston movement; and

Figure 7 is a plot illustrating the force of the 45 spring as plotted against the piston movement.

As illustrated in the drawing the device comprises a casing 10 having a housing 11 at one side thereof. The casing 10 is adapted to be disposed in the intake manifold and for this purpose the bolt holes 12 are provided. The casing 10 is provided with a fuel passage 13 that is adapted to register with the passage in the intake manifold. Within this fuel passage there is mounted an unbalanced or butterfly valve 14.

50 As shown in Figure 2 this valve is mounted on

a spindle 15 and when in wide open position is spaced from the axis of the spindle. When it is moved to closed position as shown at 14' the valve is balanced. Intermediate these two positions the forces due to vacuum and the flow of 5 gases is variable thereon.

The spindle 15 extends into the housing 11 and has an arm 16 mounted thereon with a roller 17 at the end thereof adapted to abut a piston 18. This piston is forced to the right as 10 viewed in Figure 1 by a spring 19 the tension of which may be adjusted by a screw member 20. The piston 18 fits in a cylinder 21 and is subject, through the port 22, to the reduced pressure in the intake manifold on the downstream side of the governor valve. The housing 11 is provided with a port 23 placing the interior thereof in communication with the atmosphere, so that the piston is subject on the one side to atmospheric pressure and on the 20 other to the reduced pressure in the intake manifold.

As illustrated in Figure 5, a plot of the vacuum force on the piston as against the piston movement is in the form of a curve. It is the object 25 of this invention to design the butterfly valve so that the sum of the force on the piston due to the torque on the valve plus the vacuum force on the piston when plotted against positions of the piston will give a straight line. For 30 this purpose, as previously stated, the valve 14 is eccentrically disposed with respect to its axis. When in wide open position the valve 14 is parallel to the longitudinal center line of the casing and affords practically no obstruction to 35 the passage of the gases. When in closed position the valve is horizontal as illustrated at 14'. When the valve or valve plate moves into a nearly closed position as illustrated at 14' Figure 2, the torque upon this plate will be extremely 40 small, since the two arms of the plate are of equal length and the effective lever arm due to the plate offset is nearly zero. However, it will be easy to understand that as the plate moves from fully open to closed position, the torque 45 upon the shaft increases and then decreases substantially as shown in Figure 6. By selecting the proper spacing of the plate from the center line of the axis of the spindle, it is possible to produce a torque curve such that when its effect 50 upon the piston is added to the reduced pressure acting on the piston, the combined forces represent a straight line; that is to say, the force upon the piston due to reduced pressure and torque upon the valve varies directly as the 55

movement of this piston. This combined force, therefore, can be balanced by a single spring.

The movement of the piston 18, in this structure, is very nearly proportional to the angle 5 movement of the governor valve. Consequently, the movement of the movable end of the spring is also directly proportionate to the movement of the valve.

More specifically stated when the curves of 10 Figures 5 and 6 are combined it will be found that they produce a straight line and therefore can be balanced by a single spring the action of which is shown in Figure 7.

Having thus described the invention, what is 15 claimed as new and desired to be secured by Letters Patent is:

1. A governor for internal combustion motors including in combination, a casing having a fuel passage therein adapted to be disposed in the 20 intake manifold, a butterfly valve in the fuel passage actuated in a closing direction by the flow of gases in the fuel passage, and having a variable torque curve due to such flow, said casing having a cylinder, a piston disposed therein 25 subject to the reduced pressure in the intake manifold, on the down-stream side of the valve, a spring opposing movement of the piston due to the reduced pressure and means to transmit the effect of said torque to the piston to aid the 30 reduced pressure acting thereon, said elements being so constructed and arranged that the sum of the torque effect and the reduced pressure effect form a straight line when plotted against the different positions of the piston whereby the 35 valve may be balanced in all positions by a single spring.

2. A governor for internal combustion motors including in combination, a casing having a fuel passage therein adapted to be disposed in the 40 intake manifold, a governing member in the fuel passage actuated in a closing direction by the flow of gases in the fuel passage, the closing effect due to such flow being variable, said casing having a cylinder, a piston disposed therein 45 subject to the reduced pressure in the intake manifold on the down-stream side of said governing member, a spring opposing movement of the piston due to the reduced pressure, and means to transmit the closing force on said 50 member to the piston to aid the reduced pressure acting thereon, said elements being so constructed and arranged that the sum of the closing force effect and the reduced pressure effect form a straight line when plotted against different positions of the piston, whereby the governing member may be balanced in all positions by a single spring.

3. A governor for internal combustion motors including in combination, a casing having a fuel 60 passage therein adapted to be disposed in the

intake manifold, a governing member in the fuel passage actuated in a closing direction by the flow of gases in the fuel passage, said casing having a movable element subject to the reduced pressure in the intake manifold on the down-stream side of said governing member, a spring opposing movement of said element due to the reduced pressure and means to transmit the closing force on said member to said element to aid the reduced pressure acting thereon, said governing member and said movable element being so constructed and arranged that the sum of the closing force effect and the reduced pressure effect form a straight line when plotted against the different positions of said element, whereby the governing member may be balanced in all positions by a single spring. 5

4. A governor for internal combustion motors including in combination, a casing having a fuel passage therein adapted to be disposed in the 20 intake manifold, a plate valve in said passage rotatable about an axis transverse to the passage and intersecting its longitudinal center line and offset from said axis, said valve when in full open position being parallel to said center line 25 and when closed perpendicular to the same, said casing having a movable element subject to the reduced pressure on the down-stream side of said valve, a spring opposing movement of said element due to the reduced pressure, and means to transmit the torque effect of said valve to said element to aid the reduced pressure acting thereon, the sum of the torque and reduced pressure effects on said element forming a straight line when plotted against the different 35 positions of said element, whereby the valve may be balanced in all positions by a single spring.

5. A governor for internal combustion motors including in combination, a casing having a fuel passage therein adapted to be disposed in the 40 intake manifold, a butterfly valve in said passage rotatable about a transverse axis intersecting the longitudinal center line of the passage and offset from said axis, said valve being of less length than the corresponding transverse 45 dimension of said passage and movable from a position parallel to the center line to a position perpendicular thereto, said casing having a movable element subject to the reduced pressure on the down-stream side of said valve, a spring opposing movement of said element due to the reduced pressure, and means to transmit the torque effect of said valve to said element to aid the reduced pressure acting thereon, the sum of the torque and reduced pressure effects 55 on said element forming a straight line when plotted against the different positions of said element, whereby the valve may be balanced in all positions by a single spring.
